UNITED STATES PATENT OFFICE

113,829

DESIGN FOR A KNIFE

Giacomo Agostinetto, Trout Creek, Mich.

Application July 26, 1938, Serial No. 78,750

Term of patent 7 years

To all whom it may concern:

Be it known that I, Giacomo Agostinetto, a citizen of the United States, residing at Trout Creek, in the county of Ontonagon and State of Michigan, have invented a new, original, and ornamental Design for a Knife, of which the following is a specification, reference being had to the accompanying drawing, forming part thereof.

I claim:

The ornamental design for a knife, as shown.

GIACOMO AGOSTINETTO.
